United States Patent Office

Des. 190,612

Patented June 13, 1961

190,612

HAIR DRYER

Lawrence I. Freedman, Wilmington, Del., John W. Tone, Zbleys Corner, Pa., and Seymour Rappoport, Rumson, N.J., assignors to Ronson Corporation of Delaware, Wilmington, Del., a corporation of Delaware

Filed May 3, 1960, Ser. No. 60,425

Term of patent 14 years

(Cl. D86—10)

Des. 190,612

PAGE 2

Fig. 3.

Fig. 4.

FIG. 1 is a side perspective view of a hair dryer, showing our new design;

FIG. 2 is a rear perspective view thereof;

FIG. 3 is a side elevational view; and

FIG. 4 is a front elevational view thereof with portions of the base having been omitted for convenience of illustration.

The side not shown is substantially the mirror image of the side shown in the drawings.

We claim:

The ornamental design for a hair dryer, as shown and described.
